SUPPORT FOR TELEVISION ANTENNA ELEMENTS

Dave Chapman, Chicago, Ill., assignor to The Gabriel Company, Cleveland, Ohio, a corporation of Ohio

Application December 7, 1953, Serial No. 27,966

Term of patent 14 years

(Cl. D26—14)

To all whom it may concern:

Be it known that I, Dave Chapman, a citizen of the United States, residing at Chicago, State of Illinois, have invented a new, original, and ornamental Design for Support for Television Antenna Elements, of which the following is a specification, reference being had to the accompanying drawing, forming a part hereof and wherein:

The single feature is a perspective view of a support for television antenna elements, showing my new design.

I claim:

The ornamental design for a support for television antenna elements, as shown.
